UNITED STATES PATENT OFFICE.

HENRY ROBERTS, OF HARTFORD, CONNECTICUT.

APPARATUS FOR STRETCHING WOVEN-WIRE FABRICS UPON MATTRESS-FRAMES.

SPECIFICATION forming part of Letters Patent No. 274,142, dated March 20, 1883.

Application filed January 16, 1883. (No model.)

To all whom it may concern:

Be it known that I, HENRY ROBERTS, of Hartford, in the county of Hartford, and in the State of Connecticut, have invented a new and useful Apparatus for Stretching Woven-Wire Fabrics upon Mattress-Frames; and I do hereby declare that the following specification and the accompanying drawings referred to therein properly set forth that invention forth.

10 Figure 1 represents my stretching apparatus separate from every other thing. Fig. 2 is a side view of one end of one side of a mattress-frame having my stretching apparatus applied thereto. Fig. 3 is a top view of one corner of a mattress-frame with my stretching apparatus applied to such frame.

15 A is a casting, which has a recess, b, for receiving one end of a side piece, c, of a mattress-frame.

20 D is a set-screw, which passes through a threaded hole in the bottom wall of that recess.

25 E is a bolt, which has a polygonal head, and which has a nut, F, threaded upon its smaller end, and which passes through a round unthreaded hole in the top part of the casting, and which, when the stretching apparatus is used, passes also through a similar hole in an end piece, g, of a mattress-frame, and which 30 end piece has a corner-piece, h, rigidly fastened to each of its ends by means of the screws j, j, and each of which corner-pieces has screw-holes k, k, by means of which to fasten it with screws to one side of one end of one 35 side piece of a mattress-frame.

The operation of my stretching apparatus is as follows: Each end of a woven-wire fabric being permanently fastened to an end piece of a mattress-frame, and one of those end pieces being permanently fastened at one of its ends to a corner-piece, which is permanently fastened to one side of one end of a side piece of such a frame, and the other end of the same end piece being permanently fastened to another corner-piece, which is permanently fastened to one side of one end of the other side piece of such a frame, and the other of those end pieces having permanently fastened to each of its ends a corner-piece of such 45 a frame, and the latter end piece being placed 50

as near as may be to its ultimate position over the unoccupied ends of the side pieces of that frame, the frame is ready for my apparatus. By means of the set-screw D, I temporarily but rigidly attach a specimen of my stretching apparatus to the unoccupied end of each of the two side pieces of the mattress-frame, fixing that apparatus in such a position as that the bolt E will be substantially parallel with the adjacent side piece. I next remove the nut F 55 from the bolt E of each of the two apparatuses, and then pass those two bolts through their respective holes in the adjacent end piece of the mattress-frame. I then replace both nuts upon their respective bolts, and by means of 60 wrenches I screw them up the bolts, and thereby force the end piece of the mattress-frame home to its ultimate position over the ends of the side pieces, and stretching, as I 65 do so, the wire fabric to a great tension. I 70 then fasten the two adjacent corner-pieces to their adjacent side pieces by means of screws passing through the screw-holes k, k, and thus permanently assemble all parts of the woven-wire mattress with such a great degree 75 of tension in the woven-wire fabric as makes the whole permanently useful for a bed. I 80 then remove both stretching apparatuses from the mattress-frame, and afterward use it as often as necessary for performing similar operations on other similar woven-wire mattresses.

My stretching apparatus may be somewhat modified without changing its essence or its utility. The nut F may be dispensed with, and the thread of the bolt be made to work in 85 a corresponding thread in the hole in the end piece, g. So, also, the bolt E may be reversed, and may be made to work in a nut on the outside of the casting A, or in a thread cut in the hole in that casting, through which that bolt 90 passes.

I claim as my invention—

The combination, in an apparatus for stretching woven-wire fabrics upon mattress-frames, of the casting A, the set-screw D, and the bolt E, substantially as described.

HENRY ROBERTS.
